UNITED STATES PATENT OFFICE.

ROBERT C. BENDER, OF ST. LOUIS, MISSOURI.

REFRIGERATOR DISPLAY-CASE.

980,911.

Specification of Letters Patent. Patented Jan. 10, 1911.

Application filed November 22, 1909. Serial No. 529,324.

To all whom it may concern:

Be it known that I, ROBERT C. BENDER, a citizen of the United States, residing at St. Louis, Missouri, have invented a certain new and useful Improvement in Refrigerator Display-Cases, of which the following is a full, clear, and exact description, such as will enable others skilled in the art to which it appertains to make and use the same, reference being had to the accompanying drawings, forming part of this specification, in which—

Figure 1 is a plan view of a display case of my improved construction. Fig. 2 is a vertical section taken on the line 2—2 of Fig. 1. Fig. 3 is a horizontal section taken on the line 3—3 of Fig. 2. Fig. 4 is an enlarged detail section taken on the line 4—4 of Fig. 1. Fig. 5 is a vertical section taken on the line 5—5 of Fig. 4. Fig. 6 is a perspective view of the upper end of the bearing on which the swinging arm of the cover operates.

My invention relates to a display case particularly intended for containing and displaying bulk oysters.

The particular objects of my invention are to provide a simple inexpensive case wherein bulk oysters can be kept in a sanitary condition and wherein refrigeration of the contents can be readily carried out; to arrange on the display case, a glass cover through which the oysters may be readily inspected; and to provide a case which may be easily and quickly taken apart and cleaned.

To the above purposes my invention consists in certain novel features of construction and arrangement of parts hereinafter more fully described and claimed.

In the construction of the display case as shown, 1 designates a box-like structure preferably formed of wood panels which are sheathed or covered with sheet metal. 45 Fixed on the interior of this box or receptacle adjacent the upper end is a pair of oppositely disposed segmental frames 2, and formed in the central portions of the inner faces thereof are the rectangular notches 3.

40 4 designates a circular wall of reticulated material, which wall fits snugly between the segmental frames 2, and formed on or fixed to said circular wall, adjacent the upper end is a pair of oppositely disposed lugs 5, which

55 pass through the notches 3 when the circular wall is positioned in the box or receptacle 1. After said wall has been properly seated, it is rotated a short distance in either direction, thus moving the lugs 5 into position beneath the end portions of the frames 2, 60 and firmly holding said wall in proper position.

6 designates a sheet metal cover for the box or receptacle 1. This cover is removably held on the box by means of hooks 7 or 65 like fastening devices which are pivotally mounted on the sides of the box and engage pins or projections carried by a marginal flange 6^a depending from the edge of the cover. Formed in the center of the cover 6 70 is a circular opening and the edge of said cover around this opening is flanged downwardly and inwardly as designated by 8. Seated on this flange and fixed thereto by means of cement or in any suitable manner 75 is a packing ring 9 of rubber or analogous material.

10 designates the inner container or oyster receptacle, which is preferably constructed of galvanized or enameled sheet metal 80 which construction is especially desirable in maintaining cleanliness and sanitary conditions. This receptacle 10 is in the form of a cylinder having a rounded lower end and fits snugly within the reticulated wall 4. 85 When in proper position the lower end of this receptacle rests upon the bottom of the box 1 and the upper end occupies a position immediately beneath the cover 5 and around the flange 8 thereon. Handles 11 90 are placed on the upper end of the receptacle 10 to facilitate handling.

Fixed on the rear wall of the box 1 adjacent the upper end thereof is a plate 12 and formed on or fixed thereto is a vertically disposed cylindrical bearing 13, in the top of which is formed a notch 14.

15 designates a swinging arm which is provided with a rod or shaft 15^a, which is journaled in the bearing 13, and located on 190 the portion of said shaft or rod which extends a short distance below said bearing, is an expansive coil spring 16.

A washer 17 is located on the lower end of the shaft or rod 15^a beneath the spring 16 195 and held in any suitable manner. Fixed on the under side of the arm 15 immediately adjacent the rod 15^a is a lug 18 which nor-

1 mally occupies the notch 14. The bottom 5 of the notch is rounded and the surfaces of the sides of said notch curve gradually outward away from the center of said notch and unite with the top surface of the bearing 13 in order that the lug 18 will ride freely into and out of said notch when the arm 15 is swung from one side to the other. The forward end of the arm 15 is forked 10 and extends over the top of the display case and carried by said forked forward end is a disk 19 of glass or other transparent material, which forms a closure for the opening in the top or cover 6.

15 When the arm 15 is in its normal position with the lug 18 in the notch 14, the transparent cover 19 fits snugly upon the packing or gasket 9, due to the pressure of the spring 16 on the rod 15^a and thus an air 20 and dust proof joint is formed between the cover and packing ring.

25 The contents of the receptacle 10 can be readily inspected through the transparent cover 19, and when it is desired to remove a portion of said contents, the cover 19 is manually engaged and swung to either side. In thus moving said cover the arm 15 swings upon the bearing 13 and the lug 18 rides out of the notch 14 onto the flat top 30 surface of said bearing 13. When the cover is again swung into position to close the receptacle 10 the lug 18 will drop into the notch 14 by reason of the expansive action of the spring 16, and thus the cover 19 will 35 be tightly held upon the packing ring or gasket 9. Refrigeration for the contents of the case is obtained by packing broken ice in the space outside the perforated wall 4, and thus the contents of the receptacle 10 40 are kept cool and in a fresh condition.

The perforated wall 4 prevents the broken ice from coming in direct contact with the surface of the receptacle 10 and bruising or denting the same.

45 When it is desired to take the case apart for the purpose of cleaning the same, the cover 19 is swung around to the rear of the box or receptacle 1, after which the hooks 7 are disengaged to permit the sheet metal 50 cover 6 to be removed. The receptacle 10 is now lifted from its position within the perforated wall 4, after which said wall is partially rotated to bring the lugs 5 into position where they can be drawn through the notches 3 as said perforated wall is lifted from the box or receptacle.

A display case of my improved construction is very compact, is easily supplied with ice for the purpose of refrigeration, can be easily taken apart and cleaned and maintains the oysters or like commodity in a neat, clean and sanitary condition.

I claim:

1. In a display case of the class described,

a receptacle, a pair of arcuate frames oppositely arranged within the receptacle, there being notches formed in the inner faces of said frames, a perforated wall adapted to be removably positioned in the receptacle between the frames, the lower end of which 7 perforated wall is open, and normally rests on the bottom of the receptacle, projections on opposite sides of said wall, which projections pass through the notches in the frames when the perforated wall is positioned in the receptacle, and engage beneath the frames when the wall is partially rotated in either direction, and a cover detachably arranged on the receptacle, and which cover is provided with an opening coinciding with the space within the perforated wall.

2. In a display case of the class described, an outer receptacle, an inner receptacle, a transparent cover, adapted to close the upper 8: end of said inner receptacle, an arm the forward end of which is forked and fixed to said transparent cover, a bearing fixed on the rear side of the outer receptacle, a rod carried by the arm and journaled in said 9: bearing, an expansive spring on the rod beneath the bearing, there being a notch formed in the top of the bearing, and a lug on the under side of the arm, which occupies the notch when the transparent cover 95 is in position to close the receptacle.

3. In a display case of the class described, an outer receptacle, an inner receptacle, a cover adapted to close the opening between said receptacles, a depending flange on the 10 outer edge of said cover, hooks on the outer receptacle for engaging the depending flange of the cover, there being an opening in the cover, which coincides with the opening in the inner receptacle, a flange depending 10 from the opening in the cover which flange extends into the open upper end of the inner receptacle, a packing ring on said flange, a vertically moving, laterally swinging arm arranged on the outer receptacle, 11 and a transparent cover carried by the forward end of said arm for closing the upper end of the inner receptacle, the edge of which transparent cover is adapted to rest on the packing ring.

4. In a display case of the class described, an outer receptacle, an inner receptacle, a cover detachably applied to the outer receptacle and closing the opening between the receptacles, there being an opening in 12 the center of said cover, a flange depending from the edge of said opening, a packing ring on said flange, the top of which packing ring occupies a plane above the top surface of the cover, a bearing on the outer 12 receptacle, an arm pivotally mounted in said bearing, and adapted to move vertically and swing laterally, there being a notch formed

in the top of the bearing, a lug on the arm which lug normally rests in the notch, and a transparent cover carried by the forward end of the arm, and adapted to normally rest on the projecting upper edge of the gasket to close the upper end of the inner receptacle.

In testimony whereof I hereunto affix my signature in the presence of two witnesses, this 19th day of November, 1909.

ROBERT C. BENDER.
